[57] ABSTRACT

An improved lock for a door is provided by a bar that spans both the door and the door frame thus tying these two elements together. The bar may be mounted in one of the hinges of the door. The lock may be actuated from the outside using a conventional key and a night latch, operable from the inside, may also be provided. As alternative features, the bar may be hinged to permit folding thereof, and means may be provided, for example in the form of a magnet, for retaining the bar in the folded and non-operative condition.

FIG. 7

NO ENTRY BAR LOCK

BACKGROUND OF THE INVENTION

1. Field of the Invention

This invention relates generally to locking devices and more particularly to an improved locking bar for a door.

2. Description of the Prior Art

In view of the recent increase in the crime rate, people are becoming much more security conscious and are actively seeking means for protecting their household. Substantial progress has been made in the lock art so as to make locks virtually tamper proof. However, a skilled burglar can still manage to spring the bolt of the lock by placing a tool such as a screw driver or a pry bar in the space between the door and the door frame and force the jamb away from the bolt. In this manner even the most sophisticated, pick-proof lock can be overcome.

SUMMARY OF THE INVENTION

The present invention overcomes the aforementioned shortcomings in the prior art by directly tying the door to the door frame so that the door cannot be pried open. The present invention provides a bar which may, in one embodiment, be mounted on the hinge of the door so as to extend thereacross and over the opposite door frame. A conventional lock is used having a cross pin on the inside of the room at the end of the lock opposite the cylinder. By turning the key of the lock the cross pin is rotated 90° engages and securely retains the locking bar. With the present invention, the door may be securely locked from the outside and the door is tied directly to the frame. At night a latch may be used on the inside of the room to internally secure the bar to the door. Optionally, a hinge may be provided in the bar and means, such as a magnet, may be used to secure the bar in the folded condition.

Accordingly, it is an object of the present invention to provide an improved locking assembly for a door.

Another object of the present invention is to provide an improved locking assembly for a door, as described above, that ties the door directly to the frame thereof.

A different object of the present invention is to provide an improved door locking assembly, as described above, that may be placed in the operative position from the outside of the room.

A further object of the present invention is to provide latch means for the improved door locking assembly, the latch means being operable inside the room.

Two features of the present invention are that the bar comprising the door locking assembly may be folded when not in use and also retained in the folded condition.

These and other objects features and advantages of the invention will, in part, be pointed out with particularity, and will, in part, become obvious from the following more detailed description of the invention, taken in conjunction with the accompanying drawing, which forms an integral part thereof.

BRIEF DESCRIPTION OF THE DRAWING

In the various figures of the drawing, like reference characters designate like parts. In the drawing:

FIG. 1 is an elevational view schematically illustrating the present invention in the installed and unlocked condition;

5 FIG. 2 is a perspective view, partially broken away, illustrating the bar comprising the lock of the present invention;

10 FIG. 2A is an enlarged, fragmentary elevational view, partially broken away and partially in section, illustrating one of the features of the embodiment shown in FIG. 1;

15 FIG. 3 is a fragmentary, sectional elevational view taken along line 3-3 of FIG. 1;

FIG. 4 is a fragmentary sectional elevational view taken along line 4-4 of FIG. 1;

15 FIG. 5 is a fragmentary elevational view schematically illustrating an alternative embodiment of the present invention;

20 FIG. 6 is a fragmentary elevational view illustrating an alternative arrangement of the present invention; and

25 FIG. 7 is a fragmentary plan view illustrating an adjustable feature of this invention.

DESCRIPTION OF THE PREFERRED EMBODIMENT

Referring now to FIG. 1 there is shown one embodiment of the door locking assembly 10 comprising the present invention. The locking assembly 10 includes, as shown in FIG. 2, an elongated, metallic bar 12 having a shouldered pin 14 formed integrally with one end thereof. A reduced diameter 14a of the shouldered pin 14 is used to replace the hinge pin in one of the hinges H shown in FIG. 1. The other two hinges H' need not be altered. Thus, as shown in FIG. 1, when the locking assembly 10 is in place, it spans the door D from one vertical frame member F to the other vertical frame member F'. For purposes to be described hereinafter, the bar 12 is also provided with a substantially circular opening 16 therethrough having a pair of opposed and oppositely extending slots 18 in communication with the circular opening 16. Still another rectangular opening 20 is provided adjacent a block 22 that houses an axially movable pin 24.

As shown in FIG. 3, a suitably sized and shaped hole 26 is drilled in the door D in alignment with the opening 16 in the bar 12 in order to accommodate a lock cylinder 28. A sleeve 30 is positioned within the hole 26 about the cylinder 28 and is secured to the door D by means of a plate 32 and by suitable fasteners such as screws 34. Conventional tie bolts 38 and an axially extending pin 40 complete the lock. A cross pin 42 is suitably secured in the pin 40 at the inner end thereof.

55 The diameter of the axially extending pin 40 is slightly less than the diameter of the opening 16 in the bar 12 and the axial length of the cross pin 42 is only slightly less than both the width of and the dimension between the opposed ends of the slots 18. Thus, it will be appreciated that when the key used with the cylinder 28 is turned 90° the longitudinal axis of the cross pin 42 will assume a position transverse the axis of the slots 18 and thereby securely hold the bar 12 with respect to the door D.

60 In order to tie the bar 12 to the frame F' the rectangular slot 20 in the bar 12 is used. An eye bolt 44 (FIG. 4) is suitably secured to the frame F' for example by means of bolts 46. The pin 24 may then be moved axi-

ally so as to enter the opening 44a in the eye bolt 44.

The locking assembly 10 comprising the first embodiment of this invention may be internally secured by means of the night latch 23 shown in FIG. 2A. The axially movable pin 24 is normally biased to the left and includes a hole 21 that is adapted to receive the pin of the night latch 23. Thus, when the cross pin 42 is in the horizontal position the left-hand end of the pin 24 will be in abutment therewith and will thus prevent the rotation of the lock cylinder until such time as the night latch 23 is raised.

Turning now to FIG. 5 there is shown an alternative mounting arrangement for the bar 12 comprising the present invention. Instead of removing one of the hinge pins H' as described hereinabove, a plate 50 is secured to the frame F by means of fasteners such as screws 52. The plate 50 is provided with a tubular portion or socket 55 that is sized so as to accommodate the reduced diameter section 14a of the bar 12.

An alternative embodiment of the present invention is also disclosed in FIG. 6. In the first described embodiment the cylinder 28 was positioned in the door D, in alignment with the opening 16, and the eye-bolt 44 was located in the frame F', in alignment with the rectangular opening 20. The openings 16' and 18' are again formed in the bar 12' in alignment with the axially extending pin 40" and the cross pin 42' that are part of the lock assembly but in the second embodiment the lock assembly is mounted in the frame F''. The block 22' is once again mounted on the bar 12' to the left of the cross pin 42' as shown in FIG. 6 and is used as a night latch to secure the bar 12' internally in the manner described hereinbefore. The eye bolt 44 and the rectangular slot 20 is thereby eliminated. In addition, the cross pin 42' may be made hollow to receive the axially movable pin 24'.

Optional features of the present invention may include a hinge 54 dividing the bar 12 into sections 12a and 12b as shown in FIG. 1. This construction permits the bar 12 to be folded when not in use. With the folding construction it is desirable to include some means for retaining the bar sections 12a and 12b in the folded condition and for this purpose a magnet 56 is shown mounted on bar section 12b in FIG. 1. It will be understood that, in the folded condition, the magnet 56 will releasably secure the bar section 12a.

Bar 42 or 42' serves as a hand hold to actuate the lock by hand. It may be enlarged for convenience. Tumbler 28 may be of the type which permits key actuation from the outside or night latch locking by turning bar 42 from the inside. Such lock mechanisms are conventional.

Still another feature of this invention is shown in FIG. 7. In order to accommodate doors of different widths the bar 60 is made in two sections 62 and 64 each of which have teeth, 66 and 68, respectively, that are in opposition to each other. The bar section 62 is provided with a tapped hole 70 and the bar section 64 is provided with an elongated slot 72 both of which receive a bolt 74. Other equivalent bar lengthening and shortening means may be used within the scope of the invention.

There has been disclosed heretofore the best embodiment of the invention presently contemplated. However, it is to be understood that various changes and

modifications may be made thereto without departing from the spirit of the invention.

What I claim as new and desire to secure by Letters Patent is:

5 1. A locking device for use with a hinged door and frame assembly, said locking device comprising:

- an elongated bar having first and second ends and at least one opening therethrough, said opening being intermediate said first and second ends;
- means for mounting said first end of said bar on the door and frame assembly proximate the hinged side edge of the door, said second end of said bar being releasably secured to a portion of the frame assembly remote from said first end of said bar whereby said bar spans the width of the door; and
- a lock assembly including a cylinder, said lock assembly extending through said door and frame assembly and through said opening in said bar, said lock assembly having means actuatable by said cylinder thereof for moving between a first position disengaged from said bar and a second position engaging said bar, said lock assembly being openable from a location outside of the door.

2. The locking device in accordance with claim 1 wherein said lock assembly is in the frame portion of

25 said door and frame assembly, said opening in said bar including a central portion and two opposed slots opening into said central portion, said actuatable means on said lock assembly comprising a cross pin coupled to said lock cylinder for rotation thereby and having an axis extending transversely to said axis of the cylinder of said lock.

3. The locking device in accordance with claim 2 wherein there is further included a laterally displaceable pin on said bar, said laterally displaceable pin being adapted to releasably engage said cross pin.

4. The locking device in accordance with claim 1 wherein said lock assembly is in the door portion of said door and frame assembly, said opening in said bar including a central portion and two opposed slots opening into said central portion, said actuatable means on said lock assembly comprising a cross pin coupled to said lock cylinder for rotation thereby and having an axis extending transversely to the axis of said lock, there being further included a second opening in said bar, a laterally displaceable pin on said bar and an eye bolt on said frame portion of said door and frame assembly, said eye bolt extending through said second opening in said bar, said laterally displaceable pin being adapted to releasably engage said eye bolt.

5. The locking device in accordance with claim 4 wherein there is further included latch means for selectively maintaining said laterally displaceable pin in engagement with said eye bolt and for preventing the rotation of said cross pin when said laterally displaceable pin is in engagement with said eye bolt.

6. The locking device in accordance with claim 1 wherein said mounting means comprises a pin at one end of said bar, said pin being adapted to replace the hinge pin of one of the hinges that couples the door and frame portions of the door and frame assembly.

7. The locking means in accordance with claim 1 wherein said mounting means comprises a plate adapted to be secured to the frame portion of said door and frame assembly, said plate including a tubular socket, said bar including a pin integral therewith and adapted to be received in said socket of said plate.

8. The locking device in accordance with claim 1 wherein said bar includes a hinge permitting the folding thereof.

9. The locking device in accordance with claim 8 wherein there is further included means for holding said bar in the folded condition.

10. The locking device in accordance with claim 9 wherein said holding means is a magnet.

11. The locking device in accordance with claim 1 wherein there is further included adjusting means for varying the length of said bar.
